UNITED STATES PATENT OFFICE.

JOSEPH HOLIK, OF ENNIS, TEXAS.

HANDLE-PROTECTOR.

1,128,871.

Specification of Letters Patent. Patented Feb. 16, 1915.

Application filed May 25, 1912. Serial No. 699,623.

To all whom it may concern:

Be it known that I, JOSEPH HOLIK, a citizen of the United States, and a resident of Ennis, in the county of Ellis and State of Texas, have invented a new and useful Improvement in Handle-Protectors, of which the following is a specification.

My invention relates to improvements in devices for protecting handles of axes, hammers, and other similar tools, and it consists in the construction and arrangement herein described and claimed.

The main object of my invention is to provide a device for protecting the handle 15 of a tool, such as an ax, and for stiffening it at its weakest point.

A further object of my invention is to provide means for preventing the head from flying off the handle.

Other objects and advantages will appear 20 in the following specification, and the novel features of the device will be particularly pointed out in the appended claim.

My invention is illustrated in the accompanying drawings, forming part of this application, in which—

Figure 1 is a side view of an ax, a portion being shown in section for the sake of clearness; Fig. 2 is a perspective view of the 30 protecting device; Fig. 3 is a perspective view of the clamp; Fig. 4 is a section along the line 4—4 of Fig. 2 looking in the direction of the arrows; and Fig. 5 is a section along the line 5—5 of Fig. 2 looking in the 35 direction of the arrows.

In carrying out my invention I make use of a tool such as an ax, having a blade 1 provided with the usual handle opening 2. The handle 3 is provided with the usual portion 4 arranged to enter the opening 2. The protector 5 consists of a single piece of metal shaped as shown in the drawings being tapered from one end to the other. At the larger end it is provided with a flange 45 or head 6 and at the smaller end with a flange or head 7. One side 5^x of the protector 5 is substantially flat while the other side is rounded as shown in the drawings.

In assembling the device the protector is 50 slipped through the handle opening 2 until the flange 6 engages the edge of the blade

1. The handle portion 4 is then forced into the opening 2 and secured therein in any suitable manner. A clamp 8 of the shape shown in Fig. 3 is then passed around the 55 smaller end of the protector 5 close to the flange 7. The clamp is drawn together by means of the screw 9 and nut 10 which pass through the ears 8^x.

From the foregoing description the utility 60 of this device may be readily understood.

It will be apparent from Fig. 1 that the protector 5 forms a stiffening member for that part of the handle which is weakest. Furthermore, it is on the side of the handle 65 which receives the blows from mis-licks, and which tends to wear away the handle. It is apparent that this device also aids in preventing the blade from flying off from the handle during the use of the tool owing to 70 the engagement of the flange 6 with the edge of the blade. The protector is held in a stationary position by means of the clamp 8, so that there is no danger of the parts becoming loose.

I claim:

The combination with a tool head or blade having an opening therethrough, of a handle extending through said opening, a metal protecting device having a flat portion on one side thereof extending longitudinally of said protecting device and arranged to lie next to the handle, a portion of said protecting device being disposed within said opening, an integral flange carried by each end of the protecting device, the ends of both flanges being flush with the flat side of the protecting device so as to permit the free movement of the handle into the opening, one of said flanges being arranged to engage the end of the blade or head, and a clamp disposed upon the handle contiguous to the other flange for holding the protecting device to the handle, said protecting device tapering from the flange 95 which engages the head to the flange which is contiguous to the clamp.

JOE HOLIK.
